UNITED STATES PATENT OFFICE

168,378

GARMENT HANGER

George P. Saviolidis, New York, N. Y.

Application February 9, 1952, Serial No. 18,451

Term of patent 14 years

(Cl. D80—8)

To all whom it may concern:

Be it known that I, George P. Saviolidis, a subject of the King of Greece, and residing at New York, county of New York, State of New York, have invented a new, original, and ornamental Design for a Garment Hanger, of which the following is a specification, reference being made to the accompanying drawing, forming part thereof.

Fig. 1 is a side elevational view of a garment hanger, showing my new design.

Fig. 2 is an end elevational view of the hanger of Fig. 1.

Fig. 3 is a bottom plan view of the hanger of Fig. 1.

Fig. 4 is an enlarged sectional view taken along lines 4—4 of Fig. 1 and as seen in the direction of the arrows thereof.

I claim:

The ornamental design for a garment hanger, substantially as shown.

GEORGE P. SAVIOLIDIS.
